UNITED STATES PATENT OFFICE.

ALBERT E. STRANG, OF CANTON, OHIO.

DOOR-HOOK.

SPECIFICATION forming part of Letters Patent No. 718,169, dated January 13, 1903.

Application filed October 24, 1901. Serial No. 79,854. (No model.)

To all whom it may concern:

Be it known that I, ALBERT E. STRANG, a citizen of the United States, residing at Canton, in the county of Stark and State of Ohio, have 5 invented new and useful Improvements in Door-Hooks, of which the following is a specification.

This invention relates to door-hooks, and more especially to guards for hooks designed 10 for fastening screen and other doors.

The object of the invention is to provide a guard for a hook of this character which shall be simple of construction, durable in use, comparatively inexpensive of production, 15 easily applied, and which when attached to a door and the hook is not in use will cause the hook to hang down vertically parallel with the face of the door and prevent it from being caught and held in a cocked position, as 20 is frequently the case in the ordinary hook commonly employed, which latter not only mars the door-frame, but oftentimes snags and tears the garments of persons passing through the door.

25 A further object of the invention is to provide a guard of this character which will inclose and protect the screw-eye from injury, while permitting of the free movement of the hook in engaging it with and disengaging it 30 from the eye or staple carried by the door-frame.

With these and other objects in view the invention consists in certain novel features of construction, combination, and arrangement of parts which will be hereinafter more 35 fully described, and particularly pointed out in the appended claim.

In the accompanying drawings, Figure 1 is a horizontal section of a portion of a door 40 and door-frame, illustrating the application of the invention and showing the hook engaged with an eye or staple on the door-frame. Fig. 2 is a detail view showing the position of the hook assumes when disengaged from the 45 eye or staple. Fig. 3 is a side elevation of the hook and screw-eye and a section through the guard, showing the relation of parts when assembled.

Referring now more particularly to the 50 drawings, 1 designates a fragment of the swinging stile or edge of a screen-door, and 2 designates the door-frame.

3 designates the guard, which is of hemispherical form and is provided with an inclosed socket 4, formed integral with and projecting inwardly from the outer face of the guard and provided in its rear wall with an opening 5 for the passage of the screw-threaded shank of the screw-eye 6. The hook 7 is provided, as usual, with an eye 8 at its inner 60 end, which is jointed to the eye portion of the screw-eye in the ordinary manner.

To assemble the parts, the open rear portion of the guard is brought to bear against the door and the screw-eye inserted within 65 the socket thereof, with the screw-threaded shank projecting through the opening in the wall of the socket, and then said shank is screwed into the door in the usual manner until the eye portion of the screw-eye occupies 70 said socket and bears against the rear wall thereof, thereby clamping the guard firmly in place. When the parts are thus connected up, the eye portion of the screw-eye is inclosed within the socket, which 75 guards it against injury and projects only a sufficient distance beyond the front of the guard to allow a free movement of the hook in connecting it with and disconnecting it from the eye or staple 6 on the door-frame. By 80 this construction the hook is prevented by the front wall of the guard from tilting upwardly and rearwardly to a position beyond the perpendicular, and thus becoming cocked or standing out, so as to interfere with the closing 85 of the door and snagging and tearing the garments of persons passing through the door. Hence the hook is always caused to drop downwardly, so as to lie parallel with the face of the door.

90 From the foregoing description, taken in connection with the accompanying drawings, the construction, mode of operation, and advantages of the invention will be understood without requiring a more extended explanation.

Changes in the form, proportion, and the minor details of construction may be made within the scope of the invention without departing from the spirit or sacrificing any of 100 the advantages thereof.

I claim—

In a guard for door-hooks, the combination, with a door; of a hemispherical shell having

its open rear portion bearing upon the door, said shell being stamped up from a single piece of metal and having a socket extending inwardly into the chamber of the shell to near the edge of the shell and in close proximity to the surface of the door, a screw-eye having its shank passing through the rear wall of the socket and entering the door and its eye portion substantially inclosed within the socket and clamping the shell against the door, and a hook jointed to the eye portion of the screw-eye, the socket and eye portion

of the screw-eye being of such relative size that the hook normally hangs pendent in a vertical plane and bears upon the front wall 15 of the shell, whereby it is supported in such position, substantially as set forth.

In testimony whereof I have hereunto set my hand in the presence of two subscribing witnesses.

ALBERT E. STRANG.
